UNITED STATES PATENT OFFICE.

HENRY J. PLANT, OF ROCHESTER, NEW YORK, ASSIGNOR TO DEFIANCE CHECK WRITER CORPORATION, OF ROCHESTER, NEW YORK, A CORPORATION.

CHECK-PROTECTOR.

1,352,691.

Specification of Letters Patent. Patented Sept. 14, 1920.

Application filed January 12, 1917, Serial No. 141,973. Renewed March 12, 1920. Serial No. 365,332.

To all whom it may concern:

Be it known that I, HENRY J. PLANT, a citizen of the United States, and resident of Rochester, in the county of Monroe and 5 State of New York, have invented certain new and useful Improvements in Check-Protectors, of which the following is a specification.

The present invention relates to check protectors and more particularly to the type in which a limiting line is stamped upon the check for the purpose of showing an amount beyond which the check is not payable, and an object of this invention is to provide a 15 construction which may be manufactured at a minimum cost and will be strong and durable in use.

To these and other ends the invention consists of certain parts and combinations of 20 parts all of which will be hereinafter described, the novel features being pointed out in the appended claims.

In the drawings:—

Figure 1 is a plan view of a check protector constructed in accordance with the present invention;

Fig. 2 is a section on the line 2—2, Fig. 1; Fig. 3 is a section on the line 3—3, Fig. 2;

Fig. 4 is a section on the line 4—4, Fig. 3; 30 Fig. 5 is a top view of the bottom of the casing with the ink roller mounted thereon;

Fig. 6 is a view of the under side of the platen-carrying lever;

Fig. 7 is a sectional view through a portion of a platen-carrying lever transversely of the platen;

Fig. 8 is a perspective view of the platen lever supporting frame; and

Fig. 9 is a detail sectional view of another embodiment of the platen lever supporting frame.

Referring more particularly to the drawings, 1 indicates a casing which is pressed up from a piece of sheet metal to provide 45 an open bottom, the opening being closed by a bottom plate 2. This bottom plate is formed from sheet metal and has its forward edge bent back upon itself at 3, and thence upwardly at 4 at an angle conforming 50 to the front wall of the casing 1, this upwardly-extending portion being formed with an opening or slot 5 which is adapted to receive a tongue 6 cut from the front wall of the casing 1 and bent inwardly, as shown in 55 Fig. 2. The rear edge of the bottom wall 2

has a portion bent inwardly at 7 and thence upwardly at 8, the upwardly-extending portion having the deflected end 9 and being provided with a boss 10 adapted to spring into the opening 11 formed in the rear wall 60 of the casing 1. By this arrangement, the bottom 2 is held in place by the projection 6 and the boss 10 and may be removed by introducing a finger in the notch 12 in the bottom edge of the rear wall over the rearwardly-turned portion 7 to engage said portion, in order to swing the bottom on the portion 3 as a pivot to disengage the flange 4 with the projection 6.

Within the casing 1 a printing wheel 13 is 70 arranged. This wheel is preferably hollow and comprises radial blades 13 connecting the outer cylindrical part 14 with a tubular hub part 15. The periphery of the drum part is formed with projecting parallel lines 75 of type 16 having preferably pockets in the faces of the type, and each line representing, in words or otherwise, a certain amount and having at one end thereof a corresponding amount in arabic numerals 18. These numerals may be formed by providing depressions in a blackened, smooth, enameled, cylindrical portion 17 on the drum, with the depressions filled in with a white substance. The printing drum may be supported on a 80 shaft 19 which extends through the tubular portion 15 and is journaled at its ends in the side walls of the casing 1, the cylinder being held thereto by a pin 20 passed through the sleeve or tubular portion 15 and the shaft 19, 90 the sleeve 15 projecting beyond the end of the drum portion 14 and abutting the inner face of the casing 1.

For the purpose of turning the printing wheel, the shaft 19 may carry a thumb wheel 95 21 preferably made of hard rubber or other composition, and having a screw cap 22 embedded therein for engagement with the reduced screw-threaded end 23 of the shaft 19, an anular pocket 24 being provided about 100 the reduced screw-threaded portion 23 in order that a reduced portion 25 on the thumb-wheel 21 may be received within the pocket to produce a binding action against the outer wall of the pocket, in order to prevent the free turning of the thumb wheel 105 on the shaft.

The top surface of the casing 1 serves for supporting the check, and in order that the latter may be engaged with the printing 110

wheel the top wall is provided with a slot 26, through which any one line of the type on the printing wheel may be exposed. This slot is enlarged at one end, as at 27, to expose the numerals 18 on the end of the drum, the central numeral in the opening indicating the line of type beneath the slot 26.

To the end that the check may be pressed 10 through the opening 26 on to the printing wheel, a platen 28 is employed, preferably in the form of a steel bar having its operating face 29 roughened or serrated in any suitable manner as by a plurality of pin point projections. This platen is preferably carried by a lever 30 which, in this instance, is in the form of a die casting and has the platen 29 embedded therein; said platen having transverse openings in which 15 portions 31 of metal of the die casting flow when the die casting is molded about the platen. The lever 30 may have lugs 32 depending therefrom and mounted to turn on the ends of a rod 33 which is supported by 20 two projections 34, forming the arms of a frame member arranged within the casing 1.

In the embodiment shown in Figs. 1 to 8, the platen lever supporting frame is bent up from sheet material to provide, in addition to the two arms 34, a cross piece 60 with laterally-turned ends 61 from the edges of which the arms 34 project through 25 slots or openings in the casing, the arms 34 being deflected at 62 above the top of the casing to retain the platen lever frame to the casing. In the embodiment shown in Fig. 9, the arms or projections 34^a form arms of a U-shaped member or frame, the horizontal or connecting portion 60^a of which 30 is secured on the under side of the top wall of the casing by rivets 36. A spring 37 is coiled about the rod 33 and has one end 38 engaging one of the projections 34, while 35 the other end 39 bears on the under side of the platen carrying lever 30 to hold the latter in an elevated position. To limit the upward swinging of the platen lever, the latter has one of its bearings 32 provided with a lateral projection 40 which is adapted to engage the shoulder 41 formed on one of the projections 34.

To the end that the printing wheel will have a printing line centered with reference to the platen, the platen has a smooth portion 42 which co-operates with a pawl 43 and holds the latter in engagement with a centering wheel 44 which, in this instance, is cast in one piece with the printing wheel 45 and at one end of the latter, said end in this instance being inclosed by a wall 46. The centering pawl is preferably in the form of an arm pivoted at 46 in rear of the printing wheel on one of the lateral ends 61 of the 50 platen supporting frame, and having a pro-

jection 47 to co-operate with the centering wheel 44 and a projection 48 which extends upwardly through the slot 26 at one end of the printing line for engagement by the flat surface 42 on the end of the platen. A 70 spring is coiled about the pivot 46 and has one arm 49 bearing on the pawl 43 and the other arm 50 bearing on the casing 1. This spring tends normally to hold the projection 47 into engagement with the centering wheel 44, but yields when the printing wheel is turned by the thumb wheel 21 to permit the proper line to be presented at the printing point. When the platen is depressed to engage such printing line, the 75 portion 42 engages the projection 48 and causes the projection 47 to center the printing wheel before the platen engages the type, should such wheel not be properly centered. At the same time, the printing 80 wheel is held against accidental shifting during the engagement thereof by the platen.

The inking of the printing wheel may be effected by an inking roller 51 which turns 90 loosely upon a shaft 52, the latter being extended beyond the roller and being supported in slots 53 formed in brackets 54 which are struck up from the base plate 2, one of said brackets being in advance of 95 the other so that the axis of the inking roller is at a slight angle to the axis of the printing wheel.

With the end in view of holding the inking roller yieldingly toward the printing 100 wheel, two spring arms 55 are secured to the brackets 54 and have their free ends operating in annular grooves 56 of the shaft 52 on which the inking roller turns. These spring arms are each preferably secured by 105 providing an opening 57 in each bracket 54 and bending the wire of which the spring arm is formed between its ends and extending the bend through such opening, as at 58, the other end 59 resting against the bottom 110 1.

In using the device the thumb wheel 21 is turned to bring the proper character on the indicating portion of the printing wheel in the center of the opening 27, after which the 115 check is placed face downward upon the top of the casing 1, and the handle or lever 30 is depressed, thus forcing the check against the line of type at printing position. This produces the imprint of the printing line on 120 the check and, at the same time, the fibers of the paper are broken by the pin points entering the pin pockets, so that the ink enters such fibers and thus makes the removal of the imprinted matter difficult.

The construction herein shown has but few parts and these are capable of being manufactured cheaply. There are no delicate mechanisms liable to get out of order. The platen carrying lever is connected to the 130

casing in a novel and durable manner and a simplified centering means has been provided. The inking roller is mounted in a simple and effective way and may be easily reached.

What I claim as my invention and desire to secure by Letters Patent is:—

1. A check protector comprising a casing having a slot in its top wall and two slots in rear of said slot, a printing wheel mounted in the casing and having type thereon adapted to be exposed through the first mentioned slot, a frame arranged on the inside of the casing and having two arms projecting to the exterior of the casing through the two slots, and a lever pivoted to said arms and carrying a platen for coöperation with the printing wheel.

2. A check protector comprising a casing having a slot in its top wall and two slots in rear of said slot, a printing wheel mounted in the casing and having type thereon adapted to be exposed through the first named slot, a frame arranged on the inside of the casing and having two arms extended through the second named slots, said arms having portions engaging the top surface of the casing to secure the frame in position, and a lever pivoted to said arms and carrying a platen for coöperation with the printing wheel.

3. A check protector comprising a casing, having a slot in its top wall and two slots in rear of said slot, a printing wheel mounted in the casing and having type thereon adapted to be exposed through the first named slot, a frame arranged in said casing and having laterally-turned ends provided with arms extending upwardly through the two rear slots, and a lever pivoted to said arms and carrying a platen for coöperation with said printing wheel.

4. An inking mechanism for printing machines comprising a casing in which the printing mechanism is arranged, a removable wall for the casing having slotted standards provided with openings to one side of the slots, an inking roll having a shaft working in the slots of the standards and two springs, each bent between its ends to provide two arms, one of which bears against the fixed part of the removable wall, and the

other of which bears against the shaft, the metal at the bend in the spring being extended through the opening in the adjacent standard.

5. A check protector comprising a casing, and a removable bottom wall formed with a portion at one edge bent inwardly to engage the bottom edge of the casing and thence upwardly to interlock with a portion on the inner side of one wall of the casing, said bottom wall also having a spring tongue at its opposite edge bent inwardly to engage the bottom edge of the casing and thence upwardly to cooperate with the inner face of the opposite wall of the casing.

6. A check protector comprising a casing having a slot, a printing wheel having type adapted to be exposed through the slot, a centering wheel turning with the printing wheel, a centering pawl pivoted to one side of the vertical plane of the axis of the printing wheel and having two projections near its free end, one coöperating with the printing wheel and one extending toward the slot in the casing, and a platen for coöperation with the printing wheel and said last mentioned projection of the centering pawl.

7. A check protector comprising a casing having a forward slot and two rear slots, a printing wheel arranged in the casing and having type adapted to be exposed through the forward slot, a frame arranged within the casing and having two arms extended through the two rear slots, a platen carrying lever pivoted to the arms, and a centering pawl for the printing wheel mounted on said frame within the casing.

8. A check protector comprising a casing having a forward slot and two rear slots, a printing wheel arranged in the casing and having type adapted to be exposed through the forward slot, a frame arranged within the casing and having a central portion with two laterally-turned ends provided with arms extended through the two rear slots, a platen carrying lever pivoted to said arms, and a centering pawl for the printing wheel pivoted to one of the laterally-turned ends of the frame.

HENRY J. PLANT.
